Primary Examiner — T Chase Nelson*Assistant Examiner* — Kelly L Gross(74) *Attorney, Agent, or Firm* — Fay Kaplun & Marcin, LLP(57) **CLAIM**

The ornamental design for a stethoscope head, as shown and described.

DESCRIPTION

FIG. 1 is a perspective view of a new and ornamental design for a stethoscope head;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

1 Claim, 7 Drawing Sheets# US D932,008 S
